UNITED STATES PATENT OFFICE.

WILLIAM HENRY ROACH, OF GILLIAM, WEST VIRGINIA, ASSIGNOR OF ONE-FOURTH TO JOEL T. ADAMS, OF GRAHAM, VIRGINIA.

MINE-CAR.

SPECIFICATION forming part of Letters Patent No. 734,958, dated July 28, 1903.

Application filed January 16, 1903. Serial No. 139,302. (No model.)

To all whom it may concern:

Be it known that I, WILLIAM HENRY ROACH, a citizen of the United States, residing at Gilliam, in the county of McDowell and State of West Virginia, have invented a new and useful Mine-Car, of which the following is a specification.

My invention relates to mine-cars; and it consists in improved brake mechanism especially adapted for use upon mine-cars and other cars operated upon heavy grades.

The object of my invention is to provide an adjustable brake mechanism which when adjusted in one position will be automatically actuated to apply the brakes by the striking of the buffers at the forward end of the car against any obstruction, which in any other position will cause the striking of the buffers against an obstacle to have no effect upon the brake mechanism, and which may when desired be operated by hand to apply the brakes.

In describing my invention reference will be had to the accompanying drawings, forming a part of this specification, in which—

Figure 1 is a side view showing a car provided with my invention and a portion of the track provided with means for tripping the automatic latch for the swinging end-gate of the car. Fig. 2 is a view from below of a car provided with my invention, with parts broken away to show some of the connections. Fig. 3 is a vertical section along the line 3 3 in Fig. 2. Fig. 4 is a vertical transverse section through the mine-car midway between its ends. Fig. 5 is a detail view in plan of the brake-setting cam and means for rotating the same, various positions of the parts being indicated by dotted lines. Fig. 6 is a detail view in perspective of the cam 50. Fig. 7 is a detail view looking longitudinally of the car and showing, on an enlarged scale, the parts of the brake-operating mechanism shown in Fig. 4. Fig. 8 is a detail view in plan of the ratchet 65 and pawl 66.

In all the figures above mentioned corresponding parts are indicated by the same characters of reference throughout.

Referring to the drawings by reference characters, I will first describe my automatic latch for the end-gate.

1 represents the bottom of the car, 2 and 3

its side walls, and 4 the end-gate, supported on pivots at 5 and 6.

7 represents the latch-plate having upturned ends 8 and 9, which engage with the swinging end-gate of the car.

10 is an extension of the latch-plate oppositely disposed from the upturned ends 8 and 9. The latch-plate is rigidly mounted upon 60 the rod 11, rotatably mounted in bearings 12 and 13 beneath the bottom of the car. The rod 11 is grooved at 14 and engages at that point with a forked member 15, secured to the bottom of the car, which serves to prevent the rod 11 from sliding out of engagement with its bearings. The rod 11 is bent at 16 and at 17 to form an elbow adapted to engage with a bowed member 18, secured to the track at the point where the contents of 70 the car are to be dumped. Passing through the extension 10 is a bolt 19, whose head 20 serves as a stop to limit the movement of said extension 10 away from the bottom of the car, and surrounding the bolt 19 is a 75 coiled spring 21, which tends to force the extension 10 against the head 20 of the bolt 19, and so keeps the latch-plate in operative position.

It will be seen on an inspection of Fig. 1 8c that when the elbow 17 strikes the tripping member 18, secured to the track, the rod 11 will be rotated against the action of the spring 21 as the elbow 17 rides upward over the bowed member 18 and the ends 8 and 9 of the 85 latch-plate will be drawn downward out of operative engagement with the swinging end-gate, so permitting the end-gate to swing outward and discharge the contents of the car.

The draw-bar 25 rests on the bottom of the 90 car and is secured in position by means of bolts 26 passing through slots 27 near the ends and by means of the plate 28, which is bowed longitudinally to afford a guideway for the draw-bar, and is held in position by 95 means of a bolt 29, which passes through the plate 28 through a slot 30 in the draw-bar and is prolonged beneath the bottom of the car to form a pivot on which the brake-operating cam rotates. At either end the draw-bar, which is preferably formed of wrought iron or steel, is bent back upon itself at 31, then downward at 32, and finally backward again at 33. The portion 34 between the

bends 32 and 33 forms an abutment for a spring 35 at either end, which is secured to the car. Each end portion of the draw-bar beyond the bend 33 is provided with a slot 36, 5 corresponding in position to the slot 27 in the portion of the draw-bar lying above the bottom of the car, and consequently transmitting the bolts 26, which are provided with nuts 38.

It will be plainly seen that a draw-bar constructed in the manner described will yield to jars from the sudden starting or stopping of the train of which the car forms a part and so reduce the injurious effects of such shocks upon the car.

15 The brake mechanism consists of brake members 40, provided with curved surfaces 41, adapted to engage with the peripheries of the wheels of the car and mounted upon a brake-bar 42, which extends transversely across 20 the bottom of the car about midway of its length. The brake-bar is provided with openings 43, through which pass bolts 44, which serve as guides for the brake-bar in its movement up and down as the brake members are 25 released or applied to the wheels. Passing through an opening 45 in the center of the brake-bar is a bolt 29, already referred to, and surrounding this bolt 29 is a coiled spring 46, one end of which is in contact with the 30 brake-bar 42 and the other lies against a frame 47, having the four arms 48, which are secured to the bottom of the car in any convenient manner. Rotatably mounted on the 35 bolt 29 between the brake-bar 42 and a strap 49, extending across the bottom of the car, is the cam 50, having the inclined surfaces 51, which coöperate with similar but reversely-placed inclines 52 on the upper surface of the brake-bar 42. At one side the cam 50 is 40 provided with a lug 53, which engages with a recess 54, formed in the end of a pivoted lever 55, secured by means of a bolt 56 to the bottom of the car. One of the side walls 57 of the recess 54 is considerably longer than 45 the opposite wall and is rounded at the end to form a suitable bearing-surface for engagement with the side of the lug 53.

Secured to the end of the pivoted lever 55 which is farthest from the brake-bar is a link 58, which is connected at one end with a lever 59, pivotally secured at 60 to the bottom of the car and connected at its other end with a link 61, which is pivotally connected at its other end with an arm 62, rigidly secured to a vertical shaft 63, which carries a hand-wheel 64 of the ordinary type used for setting hand-operated brakes. The shaft 63 is provided near its lower end with a ratchet 65, having three notches *a*, *b*, and *c*, with one 60 of which a spring-pressed pawl 66 is normally in engagement. Diametrically opposite the lug 53 is a similar lug 67, to which is pivotally connected a connecting-rod 68, pivotally connected at its other end with a yoke 69. 65 The yoke 69 is pivotally connected at either end to a rod 70, slidably mounted in a block 71, secured to the bottom of the car. Each

of the rods 70 carries at its outer end a buffer-plate 72, which is bent over at 73 and 74, so as to form additional guides for the rods 70. 70 Between the bent-over portions 73 and the blocks 71 are provided wear-plates 76 to protect the blocks 71 from injury from the buffer-plates. Similar wear-plates 77 are provided on the upper surface of the ends of the 75 bottom of the car to protect the car-bottom from injury from the bent-over portions 74 of the buffer-plates. Coiled around the outer portion of each rod 70 and lying between the buffer-plates 72 and the end of the bottom of 80 the car is a spring 78. Each of these springs 78 is to be made of heavy material adapted to withstand blows of considerable force and strong enough to force the buffers outward to their normal position after the springs 85 have been compressed in any wise.

The operation of the brake mechanism is as follows: Let it be assumed that the car is attached to an engine moving downgrade and that it is desired to have the brake in 90 contact with the wheels of the car in order to relieve the engine of all unnecessary load and to have the brake mechanism so arranged that when the car passes from a down to an up grade the brakes shall be automatically released. To accomplish these ends, the pawl 66 is released from an engagement with the ratchet 65, if necessary, and the brake-wheel 64 is turned until the notch *a* upon the ratchet is in position to be engaged 95 by the pawl. The cam 50 will then be in the position indicated in solid lines in Fig. 5. If pressure is now applied to the yielding buffers 12, motion will be imparted, through the rods 70, the yoke 69, and the connecting-rod 100 68, to the cam 50 in the direction indicated by the arrow *x*. This movement of the cam will cause the brake-bar 42 to be forced downward against the pressure of the spring 46 and will cause the application of the brake 105 members 40 to the wheels of the car; but as soon as pressure is removed from the buffers 72 they will be forced outward again by the springs 78, the motion of the cam will be reversed, and the brakes will be released. Now 110 whenever the car is moving downgrade it will tend to jam against the engine or car in front and force the yielding buffers back against the action of the springs, so applying the brake; but as soon as the car strikes an 115 upgrade the tendency to jam against the car in front will cease to exist and the buffers will be thrown forward by the springs and the brakes released.

If it is desired to have the brakes so adjusted that the car may be freely moved about on up or down grades without applying the brakes, the pawl 66 is to be released from notch *a* in the ratchet 65 and the brake-wheel 64 rotated until the ratchet is in position for 120 the pawl to engage with the notch *b*, when the parts of the adjusting mechanism will be in the position indicated in dotted lines in 125 Fig. 5. The yielding of the buffers 72 under

any pressure applied to them will merely cause the cam 50 to rotate in the direction indicated by the arrow *y*, and the brakes will be lifted still farther from the wheels by the 5 action of the spring 46 upon the brake-bar 42.

If when the adjusting mechanism is in the position indicated by solid lines, as best shown in Fig. 2, and the pawl 66 is in engagement with the notch *a* in the ratchet 65 the car 10 should accidentally become detached from its engine or motor, there would no longer be any pressure at the forward end of the car against the yielding buffers to apply the brakes, and to prevent the car from running 15 away in the event of such an occurrence I have provided the long end 57, forming one side of the recess 54. When the brake-wheel 64 is rotated as far as possible in the direction indicated by the arrow *z*, the end 57 engages with the lug 53 and forces it far enough 20 in the direction indicated by the arrow *x* to apply the brakes. Thus it will appear that the mechanism which operates merely to adjust the position of the cam 50 may in an 25 emergency be made to serve as a brake-applying mechanism, and when so used the brakes may be locked in position by throwing the pawl 66 into the notch *c* in the ratchet 65.

Having now fully described and shown my 30 invention, what I regard as new, and desire to secure by Letters Patent, is—

1. In a car, the combination of a brake-bar, brake members mounted on said bar, a rotary cam-plate in engagement with said brake-bar 35 and adapted to force said brake members into and out of operative position, a yielding buffer, and connections between said yielding buffer and the cam-plate whereby the yielding of the buffer rotates said cam-plate to 40 apply the brake member, substantially as described.

2. In a car, the combination of a brake-bar, brake members on said bar, inclined surfaces on said bar, a rotary cam-plate having correspondingly - inclined surfaces in engagement 45 with the inclines on the bar, a yielding buffer, and connections between said yielding buffer and cam-plate whereby the yielding of the buffer rotates the cam-plate and 50 applies the brake members, substantially as described.

3. In a car, the combination of a brake-bar, brake members mounted thereon, a cam for operating said brake-bar, a yielding buffer, 55 connections between said cam and said buffer whereby the yielding of the buffer operates said cam, and means for adjusting the position of the cam so that when the cam is in one position the yielding of the buffer causes 60 the application of the brakes and when the cam is in another position the yielding of the buffer is without effect upon the brakes, substantially as described.

4. In a car, the combination of a brake-bar, 65 brake members mounted thereon, a rotary cam-plate adapted to force said brake-bar into operative position, adjusting devices for

said cam-plate whereby when said adjusting devices are in one position the yielding of the buffer serves to apply the brakes and when 70 said adjusting devices are in the other position the yielding of the buffer is without effect upon the brakes, substantially as described.

5. In a car, the combination of a brake-bar, 75 brake members carried by said bar, a yielding buffer, connections between the yielding buffer and brake-bar, said connections comprising a rotary cam-plate, means for adjusting the position of said cam-plate so that in 80 one position of the cam-plate the yielding of the buffer causes the rotation of the cam-plate in a direction such as to apply the brakes and in another position the yielding of the buffer causes the cam-plate to rotate 85 in such direction that it has no effect upon the brakes, substantially as described.

6. In a car, the combination of a brake-bar, 90 brake members supported on said brake-bar, a rotary cam adapted to apply said brake members when rotated in one direction and to release said members when rotated in the opposite direction, yielding buffers, connections between said buffers and said cam-plate whereby the yielding of the buffers causes 95 the rotation of the cam, and means for adjusting the position of the said cam so that the yielding of the buffers will cause rotation of the cam in either direction as desired, all substantially as described. 100

7. In a car, a brake-bar, brake members supported on said brake-bar, a cam-plate, a lug on said cam, a pivoted lever having a recessed end adapted to engage with said lug, a brake-wheel and means connected therewith whereby said lever is operated to shift the position of the cam-plate, yielding buffers, and connections between said buffers and the cam-plate whereby when the pivoted lever is in one position the yielding of the 110 buffer rotates the cam in one direction and when the pivoted lever is in another position the yielding of the buffers rotates the cam in the opposite direction, substantially as described. 115

8. In a car, a brake-bar, brake members carried by said bar, a cam-plate, a lug on said cam-plate, a pivoted lever having a recessed end in which said lug fits loosely, one side wall of said recess being longer than the 120 other and adapted when the lever is swung to the limit of its movement in one direction to apply the brakes, and means comprising a hand brake-wheel and suitable connections whereby the lever is operated, substantially 125 as described.

In testimony that I claim the foregoing as my own I have hereto affixed my signature in the presence of two witnesses.

WILLIAM HENRY ROACH.
